Patented Apr. 5, 1921.

Inventor;
By Frank J. Drwar;
Milton Siffleto Atty.

UNITED STATES PATENT OFFICE.

FRANK J. DRUAR, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,374,066.

Specification of Letters Patent.

Patented Apr. 5, 1921.

Application filed November 17, 1917. Serial No. 202,507.

To all whom it may concern:

Be it known that I, FRANK J. DRUAR, a citizen of the United States, and resident of Detroit, Wayne county, State of Michigan, have invented certain new and useful Improvements in Motor-Vehicles, of which the following is a specification.

This invention relates to motor vehicles and particularly to lamps therefor.

10 In attaching lamps or headlights to motor vehicles it is very important that they should be so placed thereon that the middle rays of light from the lamps shall project in a straight line forwardly or in some 15 cases be directed downwardly slightly but to the same extent for both lamps where two lamps are used. It is not a possible manufacturing job to so make the lamps and their brackets that when fitted to the 20 vehicle the lamps will be always in exactly the right place and heretofore the lamps have been adjusted on the vehicle by bending the lamp brackets or supports slightly to bring the lamps into the correct position. 25 In some cases these lamp supports have been made so strong and rigid that this adjustment of the lamps after they are on the vehicle has become a difficult matter and it is one of the objects of the present invention to provide for an adjustment of the 30 lamp reflector and the bulb carried thereby after the lamp has been positioned on the vehicle thus dispensing with the necessity of adjusting the entire lamp body.

35 Another object of the invention is to so mount a lamp reflector within the body of the lamp that the reflector may be adjusted independently of the lamp body. Such adjustment is sometimes desirable in order 40 that the rays of light may be directed slightly downwardly without tilting the lamp body for that purpose.

45 Other objects of the invention will appear from the following description taken in connection with the drawings which form a part of this specification, and in which:

Figure 1 is partly a side elevation and partly a vertical section through a motor vehicle lamp embodying this invention;

50 Fig. 2 is a perspective detail view of a portion of the reflector of the lamp shown in Fig. 1; and

Fig. 3 is a somewhat enlarged fragmentary view of another form of the invention.

Referring to the drawings, 10 represents 55 the main body part of a lamp which is particularly adapted for motor vehicle use. It is shown as provided with lugs 11, there being one on either side of the lamp, by which it is supported upon a lamp bracket 60 12 on a motor vehicle. The lamp shown is specially designed for the use of an electric bulb and wires 13 lead through the lamp body at 14 to a socket shown in dotted lines 65 at 15 within the lamp body. A bulb 16 is 70 shown as mounted in the socket 15 and the latter is supported in a reflector 17 which is mounted in the lamp. Said reflector is preferably of parabolic form and at its periphery there is a flange 18 by which it is 75 supported in the lamp body.

The lamp body 10 is also of somewhat parabolic form and its periphery is spun out radially as at 19 and then bent back upon itself in the form of an inwardly extending flange 20 as shown in Fig. 1. This inwardly extending flange 20 carries a reflector support 21 which is detachably secured to it as by a series of screws 22, and a packing ring 23 is shown as secured between 80 the attaching flange 24 of the support 21 and the flange 20 above referred to.

The lamp is provided with a front cover 25 which is shown as hinged to the body at the top as at 26 and as provided with a detachable fastening 27 at the bottom of the lamp. This cover is of any suitable built-up construction, being provided with a lens 28, and when in closed position as shown in Fig. 1 it is drawn in tight against the packing 90 ring 23 so that the lamp is thereby made water-tight.

For the purpose of permitting adjustment of the lamp reflector 17 relative to the body of the lamp, as above suggested, the 95 reflector flange 18 is formed on one of its sides with a spherical surface 29 which is adapted to coöperate with a spherical surface 30 on the support 21. As shown, the surface 29 is on the inner side of the 100 flange 18 and the surface 30 is on the outer face of the support 21 so that as the reflector is placed in the lamp body these two surfaces are brought together as shown in Fig. 1. Preferably the spherical surfaces 105 when in position are formed about a center which is adjacent to or substantially within the lamp socket 15 above referred to so that

there will be very little movement of the bulb and its socket as the reflector is adjusted on the surface 30.

Secured to the inner face of the support 5 21 is a ring 31 adapted to reinforce the support and provide a better seat for a series of securing screws 32 which are threaded into said ring 31 through the support 21. The flange 18 is formed with a series of 10 openings 33 somewhat larger than the shanks of the screws 32 but smaller than the heads thereof so that these screws may be inserted through the openings 33 and into the ring 31 for thereby securing the reflector in 15 its adjusted position.

From this description it will be understood that by loosening the several screws 32 the reflector may be manually adjusted on the spherical surface 30 to the position desired for the best lighting effect and the screws may then be tightened to secure the reflector to the lamp in that position.

In Fig. 3 the reflector 17 is shown as having its flange 18 secured to the inner face 30^a of the support 21^a, instead of to the outer face as shown in Fig. 1. In this case also the ring 31^a is secured to the reflector flange 18 instead of to the support 21 as shown in Fig. 1. Openings 33^a are formed in the support 21^a and screws 32^a operate to secure the reflector in adjusted position as in the construction shown in Fig. 1.

In this construction shown in Fig. 3 it will be understood that in assembling the various parts the reflector 17 must be first mounted on the support 21^a before the latter is secured to the body 10 of the lamp. However, the adjustment of the reflector may be made with the same ease as in the construction 40 shown in Fig. 1 after the lamp is mounted upon the vehicle or the support.

The body 10 of the lamp shown in Fig. 3 is formed somewhat differently from that of Fig. 1 so far as its connection with the support 21^a is concerned. It has no radial flange 19 but its periphery is formed with an inwardly extending flange 20^a to which the support 21^a is directly secured as by the screws 22^a. The support 21^a is formed with 50 a radial flange 34 to which is secured a packing ring 23^a, screws 35 passing through the flange 34 and ring 23^a into a ring 36 provided for the purpose. The hinge 26 of the lamp is secured to this ring 36 and the front cover 25 and other parts of the lamp are the same as in Fig. 1.

It will be understood further that my invention is not limited to the details of construction shown and other forms may be 60 used without departing from the spirit or scope of the invention.

Having thus described my invention, what I claim and desire to secure by Letters Patent is:—

65 1. A lamp having a reflector provided

with a spherical rim portion disposed at an angle to the main body portion of the reflector and lying forward of the lamp bulb, a support for the reflector, means of engagement between such support and rim portion, the rim portion of said reflector being adjustable on said support about the horizontal axis of the lamp body. 70

2. A lamp having a reflector provided with an outwardly extending spherical flange at its rim, disposed at an angle to the main body portion of said reflector, an annular support for said flange, said reflector being adjustable in the curve of its outer surface around the horizontal axis 80 of the lamp body.

3. In a lamp, in combination with the lamp body, a reflector, said body and reflector having bearing portions provided with fitting spherical surfaces, which portions are located in front of the lamp bulb, adjacent the lens, and means for adjustably securing said bearing portions in engagement with each other. 85

4. In a lamp, in combination with the body thereof, a reflector having its curved portion spaced from said body and having a flange at its rim beyond the lamp bulb extending outwardly, a support carried by the lamp body to which said flange is adapted to be secured, means for holding said flange and body together, said flange and support having spherical surfaces permitting adjustment of the reflector relative to the body about the horizontal axis of the latter. 90

5. In a lamp, in combination with a lamp body having an inwardly extending flange beyond the front end of the lamp bulb and adjacent the front opening of the lamp, a reflector carrying a lamp bulb and spaced from the lamp body, said reflector being provided with an outwardly and angularly extending flange, means intermediate the body flange and said reflector flange for connecting said parts, said connecting means and reflector flange having engaging spherical surfaces permitting adjustment of the reflector around the horizontal axis of the lamp bulb. 105

6. In a lamp, in combination with a lamp body, an adjustable reflector having a lamp bulb secured thereto, said body and reflector having parts projecting at angles to the horizontal axis of the body and lying adjacent the front opening of the lamp and provided with concentric spherical engaging surfaces permitting an adjustment of the reflector about the horizontal axis of the body, said surfaces being described substantially on the lamp bulb as a center. 110

7. In a lamp, in combination with the lamp body, a reflector, a lamp bulb carried by the reflector, said reflector and body having engaging surfaces spherically formed 130

- and permitting adjustment of the reflector relative to the body about the horizontal axis of the latter, and means accessible from the front of the lamp for holding said reflector and body in adjusted position.
8. In a lamp, in combination with a lamp body, a reflector spaced throughout its curved surface from the lamp body, a lamp bulb carried by said reflector, said body having an inwardly extending flange beyond the front end of the lamp bulb, said reflector having an outwardly extending flange fitting said body flange, said flange being provided with spherical surfaces and screws projecting through said flanges and engaging enlarged slots in one of said parts whereby adjustment of the reflector relatively to the body about the longitudinal axis of the latter is permitted.
10. In a lamp, in combination with the

lamp body, said body having an inwardly extending flange beyond the front of the lamp bulb, a reflector adjustable with respect to said body, a reflector support secured to said body flange, said reflector having a flange extending over the support and secured thereto, and a packing ring between said support and said body flange.

10. In a lamp, in combination with a lamp body having a front opening, a reflector spaced throughout its crown portion from said body, said body and reflector having rim portions in front of the lamp bulb and adjacent said front opening, said rim portions having parts adapted to overlap and screws engaging said parts with their heads toward the front opening of the lamp.

In testimony whereof I affix my signature.

FRANK J. DRUAR.
